(57) **CLAIM**

The ornamental design for a tablet case, as shown and described.

DESCRIPTION

FIG. 1 is a perspective view of a tablet case showing my new design;

FIG. 2 is another perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof;

FIG. 8 is a bottom view thereof;

FIG. 9 is a perspective view thereof showing the tablet case in the closed status;

FIG. 10 is another perspective view thereof showing the tablet case in the closed status;

FIG. 11 is a front view thereof showing the tablet case in the closed status;

FIG. 12 is a rear view thereof showing the tablet case in the closed status;

FIG. 13 is a left side view thereof showing the tablet case in the closed status;

FIG. 14 is a right side view thereof showing the tablet case in the closed status;

FIG. 15 is a top view thereof showing the tablet case in the closed status;

FIG. 16 is a bottom view thereof showing the tablet case in the closed status;

FIG. 17 is a reference view thereof showing the tablet case in the usage condition with the tablet case opened;

FIG. 18 is another reference view thereof showing the tablet case in the usage condition with the tablet case opened;

FIG. 19 is another reference view thereof showing the tablet case in the usage condition with the tablet case closed; and,

FIG. 20 is another reference view thereof showing the tablet case in the usage condition with the tablet case closed.

The broken lines illustrate portions of the tablet case that form no part of the claimed design. The oblique line shading shown in the drawings indicates a transparent or translucent surface.

1 Claim, 14 Drawing Sheets
